UNITED STATES PATENT OFFICE.

REUBEN FRANCIS O'NEIL, OF SAN FRANCISCO, CALIFORNIA.

THIGH-ARTIFICIAL-LIMB CONTROL.

Application filed March 7, 1922. Serial No. 541,844.

This invention relates to artificial limbs, more particularly to legs, and the securing thereof to the wearer.

This invention may be best understood from a study of the accompanying two sheets of drawings, and the subjoined description thereof, taken together with the claims at the end hereof.

In the accompanying two sheets of drawing:—

Figure 1 is a front view of an individual who has lost the left leg, showing the stump of the thigh, and my invention applied thereto.

Figure 2 is a rear view of the same.

Figure 3 is a front view, showing the thigh socket and fastening means of the artificial limb, the lower part and foot of the limb being omitted.

Figure 4 is a perspective view of the shoulder harness.

In these several figures:—

The body of the wearer, 1, is shown in Figures 1 and 2, the stump of the left thigh being shown in dotted lines at 2 in those figures. At 3 is the socket for the stump 2, which receives and embraces the stump, and alines the artificial limb therewith. At 4 is a sling, which may be of cord. This cord is permanently attached in front of the wearer, to a ring 5, as at 6, and passes thence over a pulley 7, upon the outer side, thence across behind the socket 3, through a loop 8, to be presently described, thence

35 downward to a pulley 9 on the inner side of the thigh piece, and thence again to ring 5, to which it is attached by an adjustable fastening, as a buckle 10. From the pulley 7 and 9, either by direct or intermediate connection, depends a sling 11, which may be constructed of cord, and on which rides a pulley 12. The sling cord 11 extends through perforations 13 in the thigh socket, 3, so that pulley 12 may be in, about, alignment with the knee bolt 14, to which it is connected by means of an arm or lever 15, and an adjustable fastening 16, such as a strap and buckle, as shown in Figure 3.

40 The arm 15 is secured to, the knee-bolt 14, by a set screw 17, and its stirrup 18 engages the bight of strap 16.

45 The lower limb and its connections 19 are secured on knee-bolt 14, thus the lower limb

and the lever 15 move together, and need no further description.

55 The loop 8, already mentioned, is adjustably attached, as by a buckle 20, to a shoulder strap 21, which passes over the shoulder of the wearer opposite to the side on which is the artificial limb. The shoulder-strap 21, after passing over the wearer's shoulder 22, is connected, indirectly, to ring 5, as by an extension piece 23, and a buckle 24, or other form of adjustment. A snap-hook 25 may be interpolated between extension 23 and 60 ring 5 if desired.

65 To the shoulder strap 21 is connected a back brace 26 whose function is to hold the shoulder strap in alignment with the leg or thigh socket. The brace 26 is attached, at 70 one end, to a hip-strap 27, which also serves to hold the harness in place.

75 Having thus described my invention, and an embodiment of it, in the full, clear and exact terms required by law, and knowing that it comprises novel, useful and valuable improvements in the art to which it pertains, I here state that I do not wish to be limited to the precise construction and arrangement of the several parts, as herein set forth, as 80 the same may be variously modified by a skilled mechanic without departing from the spirit and scope of my invention as defined in the appended claims.

85 What I claim and desire to secure by Letters Patent of the United States, is the following, to wit:—

1. An artificial limb, comprising in combination, a thigh socket and a lower leg, means to support said parts in proper alignment, consisting of a sling having one end fixed upon one side of said thigh socket and a free end on the opposite side, a second sling passing through a pulley secured to said thigh socket and a second pulley secured to the free end of said first sling, a single shoulder strap having adjustable means at one end engaging one side of said second sling and at the opposite end a loop engaging the opposite side of said second sling, a knee-bolt secured across said thigh socket and lower leg and an adjustable strap connecting said first sling to said knee-bolt adapted to support said lower leg in position.

100 2. An artificial limb having in combination, a thigh socket, a sling adapted to sup-

port said thigh socket by connections at the sides thereof, a single shoulder-strap adjustably connected at one end to the front side of said sling and the opposite end of said shoulder-strap to the rear side of said sling, a hip-strap connected to the front and back of said shoulder-strap, and a brace secured at one end to the back of said shoulder-strap

and at its opposite end to said hip-strap, said hip-strap and brace adapted to hold said shoulder-strap in alignment with the leg. ¹⁰

In testimony that I claim the foregoing I have hereto set my hand this 27 day of Feb., 1922.

REUBEN FRANCIS O'NEIL.
